UNITED STATES PATENT OFFICE.

JAMES REYNOLDS AND JOHN WILSON, OF CLEVELAND, OHIO; SAID WILSON ASSIGNOR
OF HIS ENTIRE RIGHT TO REYNOLDS.

BEAM AND JOIST CHAIR.

Application filed December 26, 1924. Serial No. 758,011.

This invention relates to a support or chair for concrete reinforcing bars such as generally used in the construction of concrete beams and joists.

The general object of the invention is to provide a chair which may be formed from a single strip of material into a rigid supporting member capable of being very easily and cheaply manufactured and used in varying lengths depending on the number of bars it is desired to support.

In forming concrete joists usually two reinforcing bars are used, one to lie flat at the bottom of the joist and the other to be bent upwardly at its end to form a trussed reinforcement for the joist. In the case of a wider beam, four or six bars are usually used alternating horizontal and trussed bars. It is very seldom that one reinforcing bar alone is used for such a purpose. The chairs which we have shown in two modifications may be made from a single strip of material such as a round bar or wire, a suitable size being 8 or 10 gauge. It is desirable to support the reinforcing bars a slight distance above the false-work or pouring form which runs the entire length of the beam to be poured from concrete. For this purpose a very low chair is most desirable, to so position the bars as to attain the maximum of reinforcement therefrom. That is to say the bars should be supported close to the floor of the false-work, yet provide room for the concrete to flow beneath the bars to adequately cover them and protect them from rust.

We have found that by looping a continuous piece of rod first into comparatively open and then into substantially closed loops that by simply bending a predetermined portion of each of the closed loops downwardly first in one direction then in another and repeating, a very cheap and satisfactory chair is formed. By cutting off sections at this formed structure comprising a portion of two of the closed loops which includes between them a single complete closed loop and a pair of the open loops, a very strong chair may be formed for supporting a pair of reinforcing bars. Provision has been made in a modified form for cutting the strip to support only one bar and it will be apparent that either embodiment may be cut to support any number of bars.

Other features and objects of the invention

will become apparent in the further description which relates to the accompanying drawings wherein we have shown the preferred form. The essential characteristics will be summarized in the claims.

In the drawings, Fig. 1 is a perspective of a chair adapted to support four reinforcing bars; Fig. 2 is an end elevation thereof; Fig. 3 is a perspective of a slightly different form of chair; Fig. 4 is an end elevation thereof; Fig. 5 is a sectional perspective of a portion of a floor under construction showing a pair of reinforcing bars supported on our chair; Fig. 6 is a side elevation of a complete chair formed by cutting in half the chair shown in Fig. 1; Fig. 7 is a side elevation of the chair shown in Fig. 3; Fig. 8 is a plan view of a pair of columns connected by false-work for forming a beam, showing four reinforcing bars supported thereon on our chairs; Fig. 9 is a sectional side elevation of the bars and false-work shown in Fig. 8.

The rod or strip to be bent may of course be originally straight or on a roll. The open and closed loops placed therein as a first operation of forming are indicated in Fig. 6, at 5 and 6 respectively. The loop 5 preferably has a middle portion cradle for centrally supporting a reinforcing bar or the like and the sides 7 thereof extend upwardly as shown. One of these sides is a part of the first closed loop 6 while the other ends at the bend 8 from which the material extends downward to form the end leg 6^a. This may be considered as part of an original closed loop 6 sheared at its lowermost point. The first loop 6 is bent downwardly at 9 and extends outwardly to form the leg 10 on one side of the chair as shown in Fig. 2, while on the other side the next succeeding loop, designated 6^b extends downwardly in the reverse direction. The next loop indicated at 6^c is bent down in the same direction as the loop 6 so as to produce an alternate disposition of legs each being in a plane in common with either the legs 6 or 6^b. All the open loops 5 are substantially alike and occupy the same vertical plane. In Fig. 6, we show a complete supporting chair for a pair of reinforcing bars formed by cutting in two the chair shown in Fig. 1. We have found that by cutting the outer or bottom end of the loop 6^a substantially in the middle, a slight foot

is formed on the lower end of the leg, as shown in Figs. 1 and 6 at 13.

This chair may be handled in a construction job in a continuous long series and the 5 desired number of loops may be sheared off in multiples of two such as shown in Fig. 6, four as shown in Fig. 1, or as many as may be desired.

As shown in the modified construction 10 (Figs. 3, 4 and 7) we have added somewhat to the stability of the chair by forming an extra closed loop. In other words with reference to Figs. 3 and 7 considering the operation of making the chair as beginning at 15 the open loop 15, the first closed loop formed is that indicated at 16, and the second 17, the material extending beyond the last loop to form the loop 18. This portion as before is substantially in the same vertical 20 plane as the loop 15 and about the same height. The loops 16 and 17 may be bent downwardly in opposite directions as at 19 in the same manner as before.

Referring especially to Figs. 3 and 4, it 25 will be seen that the outer ends of the chair are formed of horizontally disposed portions 20. This is attained by cutting the middle span between the two closed loops 16 and 17 as at 21, and bending down the 30 free ends into a substantially straight floor engaging member. It is to be understood, of course, that the chair is self-supporting without this additional foot and in most cases need not be resorted to; that is to say 35 the outer end of the sheared closed loop might remain projecting upwardly.

In Fig. 5 we have shown the single pair of reinforcing bars B and B' as supported on such a chair as shown in Fig. 3. The 40 chair rests on false work C which may be the so called "metal dome" sheeting which is used for a form in such concrete construction. The portion of the false work C' extending downwardly from the general 45 plane forming the joists for the upper portion C' supports the floor or ceiling. The end of the bar B it may be supposed, may rest on a higher chair to prevent its falling sideward or may be secured to vertical reinforcing bars not shown. The chairs not 50 only serve to support the reinforcing bars in place but by reason of the overhanging ends of the chair, the bars are spaced apart from the form C'.

In Figs. 8 and 9 a pair of column forms are indicated at D and D' having suitable reinforcing bars D² extending vertically therein. The false work E for supporting the concrete for the beams extends across 55 and is supported by the false work for the column. Two chairs 1 and 2 are shown as supported on this false work. As shown in Fig. 8 the straight bars B' fall short of entering the columns and are therefore entirely supported by the chairs, while the

trussed bars B alternately placed with reference to the straight bars extend outwardly through the vertical reinforcement, usually through the column cap shown at F and this upper end of the bar B' is retained 70 against falling by the vertical bars.

By varying the gauge of rods from which the chairs are formed, the chairs may support reinforcing bars of almost any weight commonly used, since when the weight of 75 the bar is increased the distance between the bars is increased accordingly, and therefore the bends in the material necessary to form the cradle-like support and the supporting legs are no sharper than for lighter 80* chairs.

It will be seen that we have provided a very simple chair for this purpose which may be made in any length for supporting any number of bars and from which any 85 length may be easily cut up to form shorter units for supporting simply a pair or even one bar.

If it is desired to support simply a single bar the form of chair shown in Fig. 3 would 90 be used, in which case the chair therein shown could be sheared in two at 21^a and the bends adjacent the shearing point bent down as at 20. With reference to Fig. 4, it will be seen that the supports so formed 95 would be entirely adequate since the weight indicated at B' would be directly over the central portion of the two horizontally disposed portions 20.

Having thus described our invention, we 100 claim:

1. A chair for supporting concrete reinforcing bars comprising a continuous member formed into a plurality of upright substantially U-shaped bends in mutual alignment and vertically disposed, the member continuing into longer bends between each adjacent first named bend, the adjacent longer bends being on opposite sides of the plane of the U-shaped bends, whereby a three 105 point support is provided for a bar carried by either or two adjacent U-shaped bends. 110

2. A support for the purpose set forth, comprising a single piece of wire or the like formed to provide vertically extending open loops, in the same plane the wire intermediate the loops being bent downwardly in a narrow loop at an angle to the plane of first named loops, and the free ends of the wire being bent downwardly from the remote 120 ends of the first named loops and in a plane intersecting both aforesaid planes at a common line, whereby bars may be suspended from the said end portion and narrow loop at points below the said intersections of 125 planes and intermediately of the remote planes.

3. A device of the character described comprising a single piece of wire or the like formed to provide close and open loops, 130

- there being one close loop between adjacent open loops, the remote ends of the wire being bent downwardly from respective upper ends of the most remote open loops, said 5 open loops being in a vertical plane and each adapted to support a weight such as a bar along the lowermost portion thereof, the sides of the loop preventing lateral shifting of the weight, and the close loop and end 10 portions being disposed in respective planes intersecting along a line directly above the supporting portions of the open loops, whereby the load is suspended from the upper ends of the close loop and remote end 15 portions, and whereby the device will stand upright irrespective of whether all or a portion of the open loops bear such weight.
4. A one piece supporting unit comprising aligned and separated portion in a horizontal plane, a narrow loop joining the adjacent ends of said portions extending upwardly and vertically for a short distance and then downwardly at an angle to the vertically extending portion, the other ends of 25 each separated portion extending first up-
- wardly and vertically, then downwardly at an angle similar to that of the narrow loop but on the opposite side of the horizontal portions, whereby a bar may be suspended from the loop and end portions and be prevented from lateral displacement by these 30 elements.
5. A support for concrete reinforcing bars comprising a member having substantially vertically disposed aligned loops open upwardly to support bars and maintain them against lateral shifting, a longer loop connecting said vertically disposed loops and extending downwardly at one side of the plane of such loops and adapted to serve 35 as a supporting leg, and leg portions formed at the outer ends of said vertically disposed loops, said leg portions extending downwardly on the other side of said plane and then flatwise along the surface upon which 40 the support is adapted to rest.
